UNITED STATES PATENT OFFICE.

JULIUS PROEGER, OF GREENSBURG, PENNSYLVANIA.

DESIGN FOR A VESSEL.

SPECIFICATION forming part of Design No. 21,181, dated November 24, 1891.

Application filed May 25, 1891. Serial No. 394,065. Term of patent 3½ years.

To all whom it may concern:

Be it known that I, JULIUS PROEGER, of Greensburg, in the county of Westmoreland and State of Pennsylvania, have invented a new and original Design for Table-Ware, of which the following is a full, clear, and exact description, reference being had to the accompanying drawing, forming part of this specification, and which represents a perspective view of a vessel embodying my design.

The leading feature of my design consists in a vessel provided on its outer surface with an encircling series of concave faces tapering outwardly at their lower ends to meet a series of flat faces located on an integral ring, which is of greater diameter than the body of the

vessel, and which ring is intersected by one or more series of diamond-shaped depressions.

In the drawing, 2 represents the body of the vessel; 3 3, the concave faces; 4 4, the flat faces, and 5 5 the diamond-shaped depressions.

I claim—

The design for a vessel, substantially as herein shown and described.

In testimony whereof I have hereunto set my hand this 22d day of May, A D. 1891.

JULIUS PROEGER.
